LOUISIANA.

BACKED AND INTERLINED BOW FOR USE WITH ARROWS.

Application filed April 8, 1926. Serial No. 100,731.

This invention relates to archers' bows and has for its object to provide an improved backed or interlined bow which is simple and inexpensive to manufacture and which 5 has all the good qualities which a bow should have besides possessing additional good qualities.

In order to give a better understanding of the advantages gained by our invention we 10 will first refer briefly to the various steps considered necessary in the construction of ordinary bows and in general what has been done heretofore in constructing backed bows and laminated bows.

15 The ordinary bow without any backing, in order to be useful and to stand up under the strain of constant bending for any length of time must be constructed with great care.

In most woods the grain must be carefully 20 followed throughout, the bow must be left larger when tiny knots or flaws appear and great caution must be used not to bend the finished bow even an inch or two too far: all this to avoid fracture. Even in the case of 25 woods where the grain is interlocking and does not need to be carefully followed considerable caution must still be exercised. Considerable care must be used in selecting the best side of the stave (the stave is a stick 30 from which a bow is made) for the back, as a small imperfection occurring at this point of greatest strain will usually cause a break.

Heretofore, to eliminate the danger of 35 breaking, bows have been backed with hickory, or raw hide or similar animal tissue such as cat gut and whale bone. All of these materials prevent breaking to a greater or lesser degree but have the disadvantage of slowing down the bow so that it will not 40 shoot as far.

The explanation of this is that when the bow is fully drawn the back is under a great stretching strain, while the belly is under a great crushing strain and at some point between the two the wood of the bow is under 45 a great shearing strain. This means that the back must be high in tensile strength, the belly must be high in crushing strength and the central portion of the bow must be high 50 in shearing strength. As noted before, the hickory, raw hide or other backing adds to the tensile strength of the back but also slows down the action of the bow.

Then, too, many bows which are made of 55 laminations of two or more woods tend to

shear or break at the joints because of the difficulty, especially in the case of very hard woods, of making a glue joint the full length of the bow between the various laminae without the slightest imperfection or weak spot 60 in the said joint. A small spot the size of a dime in which the two woods do not adhere perfectly to each other is sufficient to cause the entire bow to come apart at the joint as the strain in many instances is hundreds of pounds to the square inch.

We are especially desirous of pointing out here that any bow, either backed or not backed, which has been heretofore constructed, and has stood up under a very hard degree of actual use requires very select material and takes time and pains to construct, all of which adds to its cost of manufacture.

As stated above one of the objects of our present invention is to provide a novel 75 archer's bow which will compare very favorably with the best, and consequently expensive, bows which have been heretofore made but which can be made relatively inexpensively and which does not require such 80 fine selection of materials as has heretofore been considered necessary in constructing the better class of bows.

In carrying out our invention we provide the limbs of the bow with a backing of paper 85 fibre which has a relatively high tensile strength. We have found from experiment that the use of the paper fibre strengthens the bow and increases the distance which the bow may be drawn with safety but at the 90 same time does not slow down the bow or deleteriously affect its cast. In fact, a bow backed with the paper fibre in accordance with our invention has an improved cast over a bow not so backed.

95 The limbs of the bow embodying our invention may either have a laminated structure or may be of a single piece of wood except for the backing. In the case of a laminated structure we propose to make 100 each limb of laminations of wood and paper fibre, each laminated limb being backed with the paper fibre as above described.

In order to give an understanding of the invention we have illustrated in the drawing some selected embodiments thereof in which—

Fig. 1 is a side view of a bow embodying our invention;

Fig. 2 is an enlarged fragmentary view 110

showing parts of one of the limbs of a laminated bow embodying our invention;

Fig. 3 is an enlarged section on the line 3—3; Fig. 2.

5 In Fig. 1 of the drawings 1 indicates generally an archer's bow having the two limbs 2 and 3, the handle portion 4 and the string 15. In the case of a so-called "self" bow the body of the bow is made from a single bow stave which is shaped to form the two limbs 2 and 3, the handle 4 being in the form of a wrapping which is applied to the center portion of the bow. In accordance with our invention the bow is provided with a backing 5 of paper fibre which is secured to the back of the bow throughout its length. Ordinary commercial paper fibre is suitable for this purpose, it being desirable, however, that the paper fibre should 10 be relatively thin. This paper fibre can conveniently be applied to one face of the bow stave before the bow is shaped therefrom, the fibre being secured to the bow stave by glue or any other suitable adhesive. 15 After the fibre ply has been thus secured to the bow stave the latter may be worked down in usual way to fashion the bow.

While the backing 5 may have fairly high tensile strength yet because it is relatively thin it adds no appreciable tensile strength to the back of the bow.

One of the important results accruing from the use of our improved backing is that the latter serves to bind down the fibres in the back of the bow and thereby prevent an initial splinter from forming which might eventually cause a fracture of the bow.

We are aware that bows have heretofore 40 been backed with hickory, raw hide and similar material but so far as we know in every case the backing is of considerable thickness and has for its principal object to take the tensile strain to which the back of the bow is subjected, it being understood that when the bow is drawn the back of the bow is under high tensile strain while the belly is under a high compressing strain. The object of the relatively thick backing 45 of raw hide, hickory or other material which has been heretofore used is to furnish the necessary tensile strength to the back of the bow. It is found, however, that while a relatively thick backing may add the desired 50 tensile strength to the bow which will prevent it from breaking yet it tends to slow

down the action of the bow and reduces its casting qualities. In the case of our present invention, however, the fibre backing is relatively thin (it preferably being not over one thirty-second of an inch ($\frac{1}{32}$ ")) 60 thick and good results being secured with a backing considerably thinner), and is not intended to supply the tensile strength to the back of the bow, the wood of the bow 65 itself being relied on for this purpose. The relatively thin fibre backing of our invention adds very little tensile strength to the back of the bow, one of its prime functions being to bind down the fibres at the back of 70 the bow and thus to prevent the formation of an initial splinter.

We find from experiments, however, that a bow backed with fibre has an improved cast over a similar bow not so backed so 75 that a fibre backed bow is not only less liable to break than a bow not so backed but it has improved casting qualities.

In Figs. 2 and 3 we have shown a laminated bow embodying our invention. In 80 the construction shown in said figures each limb of the bow is made up of a plurality of laminations comprising strips of wood 6 alternating with strips of fibre 7, the wood and fibre strips being firmly glued together. 85 In this embodiment also the back of the bow has the fibre backing 5 as shown in Fig. 1.

Having thus described the invention, what is claimed is:

1. An archer's bow provided with wooden limbs which are backed with a thin layer of paper fibre, said backing strengthening the bow against breaking without decreasing the cast of the bow.

2. An archer's bow, the limbs of which are formed of alternate laminations of wood and paper fibre, said laminations extending parallel to the back, both limbs being backed with said paper fibre.

3. An archer's bow provided with wooden limbs which are backed with a thin layer of paper fibre, said layer strengthening the bow against breaking without decreasing the cast of the bow by binding down the fibres of the wood and thereby preventing an initial splinter from forming.

In testimony whereof we affix our hands this fifth day of November, 1925.

PHILLIP ROUNSEVELLE.
ELIZABETH ROUNSEVELLE.
